COMBUSTION ENGINE VALVE OPERATING
MEANS

Gustav Pielstick, Saint-Germain-en-Laye, France

Application October 5, 1949, Serial No. 119,610
In France October 12, 1948

2 Claims. (Cl. 123—90)

1

This invention relates to valve-operating means for operating the intake and exhaust-valves of internal combustion engines and the like. The invention is more particularly directed to such engines of the four-stroke type including two intake and two exhaust valves.

In four stroke engines in which the cylinder-head comprises two intake and two exhaust valves, the valves are generally operated by two pairs of interconnected rocker levers, or by a group of valve-operating levers provided with bearing supports and rocker pivots at different vertical heights. Whatever the particular arrangement used however the number of such bearings and pivots in conventional engines is high and consumes much space on the cylinder head, and accessibility of the valves is seriously impaired.

It is a general object of this invention to overcome this drawback and provide an improved operating assembly for the intake and exhaust valves of a combustion engine.

It is an object to provide an operating rocker leverage for operating the valves of such an engine which is simpler in operation, and provides freer access to the valves, than in prior art.

Another object is to provide such a leverage which is improved in that it includes a lower number of pivotal parts.

With the above and further objects in view, I provide a valve-operating leverage of the type described which essentially comprises a rocker lever to operate the exhaust valves, said rocker lever comprising integral angularly displaced arms in equal number to said exhaust valves extending from a common oppositely-projecting arm adapted to be actuated by a tappet or the like. Preferably said arms form a fork with divergent tines symmetrically disposed with respect to a radial plane of the cylinder. The intake-operating rocker means may according to the invention comprise a plurality of parallel-spaced integral arms in equal number to said intake valves and a common integral oppositely extending arm adapted to be actuated by a related tappet or the like. Preferably said parallel-spaced arms are symmetrically disposed on each side of said radial plane and of the said common oppositely-extending arm of the exhaust-operating rocker, while said oppositely-extending arm of the intake-operating rocker is offset to one side of said plane. The rocker shafts for said intake and said exhaust rocker means may be mounted on a common support or on separate supports. The said oppositely-extending arms of

2

each rocker may be operated from respective tappets, and these tappets may extend higher at an angle to the vertical or vertically. In the first case the parallel-spaced arms of the intake rocker are preferably interconnected by the actual common rocker shaft thereof, while in the second case the arrangement is such as to make it preferable to provide said integrally interconnecting means for the parallel spaced intake rocker arms in the form of a bridging member. The rocker shaft for the intake rocker may be both vertically and horizontally offset with respect to that of the exhaust rocker, and preferably the intake rocker shaft is displaced in a horizontal plane radially outwardly of the exhaust rocker shaft. Further features of my invention will appear as the description proceeds.

Exemplary embodiments of the invention will now be described in greater detail, by way of illustration and not of limitation, with reference to the accompanying drawings, in which:

Fig. 1 is an overhead plan view of a first embodiment, showing the improved valve-operating means of my invention as applied to a four-valve engine;

Fig. 2 is a partial view in sectional elevation on line II—II of Fig. 1;

Fig. 3 is a partial sectional elevation on line III—III of Fig. 1;

Fig. 4 is an overhead plan view relating to a modification and Fig. 5 is a sectional elevation on line V—V of Fig. 4.

As shown in Figs. 1 to 3, a combustion engine cylinder head 1 comprises an injection nozzle 2, two intake valves 3, 4 and two exhaust valves 5, 6. The intake valves 3, 4 are operated by a pair of respective levers 7, 8 pivoted on a common shaft 9. The shaft 9 is actuated through a single lever arm 10 by a valve-lifter or tappet 11. The exhaust valves 5, 6 are operated by a fork-shaped lever 12 which includes two integral lever-arms or tines 13, 14 angularly displaced in a horizontal plane from each other, extending from a common opposite arm 12. The exhaust valve operating lever 12—13—14 is pivoted on a rocker shaft 15 and its arm 12 is actuated by the exhaust tappet 16. It will be noted that the exhaust-valve operating lever arms or tines 13, 14 are of equal length and are symmetrically disposed on each side of the injector nozzle 2, and also that the entire arrangement of intake- and exhaust-valve actuating lever arms 7, 8 and 13, 14 as a whole is symmetrical about a diametric plane of the cylinder head.

The pivot shaft 9 for the intake-rocker is hori-

zontally offset from the pivot shaft 15 for the exhaust-rocker. Both pivot shafts however as here shown are supported on a common mounting support 17, as shown in Fig. 2. The tappets 11 and 16 for the intake and exhaust rockers respectively are in this embodiment inclined at an angle to the vertical.

The embodiment illustrated in Figs. 4 and 5 differs from the one just described mainly in that the respective rocker members 7-8 for the intake valves and 12-13-14 for the exhaust valves are so formed as to be actuated by vertically extending tappets 11 and 16 respectively. In this embodiment the intake rocker arms 7 and 8 are integrally connected by a bridging member 18 having an integral bridging portion 19.

It will of course be understood that various modifications may be made in the structural details of the exemplary embodiments shown without departing from the scope of the invention.

What I claim is:

1. In a valve operating assembly adapted for use in an internal combustion engine having at least two exhaust and two inlet valves, two separate rocker means for the actuation respectively of the exhaust and inlet valves of the engine, an individual pivot means for each one of said rockers, the axes of said pivot means being separated by a certain distance and located at the same horizontal level, and push-rod means located alongside the cylinder and adapted to act on one end of said rockers so as to cause their tilting and thereby the control of the valves by their other ends beyond the pivot axes, these latter

5 pivot axes being situated on said rockers substantially midway between the points of these latter acted upon by the push rods and acting upon the valves, the said rockers having each at least two arms each of which corresponds to a respective valve, the contact points of said push rods and rockers being situated on a line which is substantially parallel to the longitudinal axis of the engine and forms an acute angle with the 10 pivot axes of said rockers, said latter axes being substantially perpendicular with respect to the general longitudinal direction of these rockers.

2. Assembly according to claim 1 wherein a single support is provided for the mounting of both said individual pivot means.

GUSTAV PIELSTICK.
